UNITED STATES PATENT OFFICE.

PHOENIX M. GUTLEBER, OF LIBERTY CORNER, NEW JERSEY.

TRACE.

SPECIFICATION forming part of Letters Patent No. 699,918, dated May 13, 1902.

Application filed July 13, 1901. Serial No. 68,174. (No model.)

To all whom it may concern:

Be it known that I, PHOENIX M. GUTLEBER, a citizen of the United States, residing at Liberty Corner, in the county of Somerset and 5 State of New Jersey, have invented a new and useful Trace, of which the following is a specification.

This invention relates to harness, and particularly to draft connections, and has for its 10 object to ease the draft upon the shoulders of draft-animals, thereby to obviate sore shoulders, and also to provide for easing the strain, particularly when starting a vehicle.

It is furthermore designed to arrange for independent endwise movement of the traces, so as to accommodate for unequal strain thereon, and also to provide for automatically taking up the slack in either trace which is due to abnormal strain on the opposite trace.

20 Another object resides in arranging for the convenient application and removal of the trace forming the general feature of this invention and to provide for applying the same to form a connection between a harness-collar and a draw-bar or whiffletree without materially altering these parts or any other parts of the harness.

With these and other objects in view the present invention consists in the combination 30 and arrangement of parts, as will be herein-after more fully described, shown in the accompanying drawings, and particularly pointed out in the appended claims, it being understood that changes in the form, proportion, size, and minor details may be made 35 within the scope of the claims without departing from the spirit or sacrificing any of the advantages of the invention.

In the drawings, Figure 1 is a side elevation 40 showing the present invention in its applied position. Fig. 2 is a detail perspective view of a trace embodying my invention.

Like characters of reference designate corresponding parts in both figures of the drawings.

45 Referring to Fig. 1 of the drawings, there has been illustrated a harness-collar 1, having the usual hames 2, and it is the purpose of the present invention to form an improved 50 draft connection between the collar and the draw-bar or doubletree 3, which is commonly

provided with a pair of whiffletrees, one of which has been indicated at 4.

In carrying out the present invention there is provided a pulley-block 5, having a suitable snap-hook 6, which is designed to be engaged with a suitable ring or hook 7, carried by the whiffletree, so as to be detachably connected to the draw-bar. The forward end of this block is provided with a hook 8, to which 60 is connected one end of a trace 9, which may be formed of rope or other suitable material and is reeved through a guide or pulley block 10, carried by the harness-collar, from which guide the trace returns to and is reeved 65 through the block 5 and then carried forwardly and rigidly connected to the collar. The forward end of the lower trace portion 11 is connected to the collar by means of a strap-and-buckle connection 12, that is carried by the usual hame-staple 13. The guide or pulley 10 has an elastically-yieldable connection with the collar by means of the opposite coiled or helical springs 14, which have their rear ends connected to the block, from 70 which they diverge, and have their forward ends connected to the hame, the lower spring being connected to the staple 13.

When the draft-animal moves forwardly, a tension is immediately placed upon each trace, 80 as the part 11 thereof is rigidly connected to the harness-collar, and therefore must move forwardly with the animal; but by reason of the springs 14 the block or pulley 10 yields in a rearward direction, whereby a sudden 85 jerk or strain is relieved from the shoulders of the animal, and in view of the fact that the contiguous trace has its opposite ends fixedly connected to the collar and the draw-bar a portion of the draft is applied to the 90 draw-bar, so that the latter moves forwardly simultaneously with the animal, but at a less rate of speed, until the springs 14 have become fully stretched, after which the movement of the animal and the draw-bar will be 95 simultaneous. However, should the wheels of the vehicle strike a rut or other obstruction the jar caused thereby will be taken up by the springs 14.

From the foregoing description it will be 100 seen that the springs afford an elastically-yieldable element to take up any sudden jerk

or strain, and thereby obviate rubbing of the collar upon the neck of the draft-animal. This easing action of the springs is particularly advantageous in starting a vehicle, as said springs will yield under the first strain, and thereby apply the draft gradually.

By reason of the endwise movement of the trace, due to the mounting thereof in opposite blocks or guides, and the elastic connection between the doubled portion of the trace and the collar any slack is automatically taken up, so as to obviate looseness or sagging of the trace, and thereby maintain the same in a comparatively taut condition.

15 It will be noted that the present form of trace may be applied without altering or changing the collar, the draw-bar, or any of the parts of the harness, and therefore is complete in itself and may be applied to take the place of common traces.

What I claim is—

1. A draft connection consisting of opposite pulleys, one of which is provided with an elastic fastening, and a flexible trace having

its intermediate portions reeved through the opposite pulleys, one end of the trace being fixed to the other pulley and the opposite end of the trace having a fastening for engagement with the part to which the first-mentioned pulley is to be connected. 30

2. A draft connection, consisting of opposite pulleys, one of which is provided with angularly-related spring-fastenings for engagement with a harness-collar, and the other being constructed for connection to a draw-bar, 35 and a flexible trace having its intermediate portions reeved through the opposite pulleys, one end of the trace being fixedly connected to the said other pulley, and the opposite end of the trace having a collar-engaging fastening. 40

In testimony that I claim the foregoing as my own I have hereto affixed my signature in the presence of two witnesses.

PHOENIX M. GUTLEBER.
